UNITED STATES PATENT OFFICE.

JUSTUS A. TRAUT, OF NEW BRITAIN, CONNECTICUT, ASSIGNOR TO THE STANLEY RULE AND LEVEL COMPANY, OF SAME PLACE.

DESIGN FOR A TOOL-HANDLE.

SPECIFICATION forming part of Design No. 26,769, dated March 16, 1897.

Application filed January 26, 1897. Serial No. 620,837. Term of patent 14 years.

To all whom it may concern:

Be it known that I, JUSTUS A. TRAUT, a citizen of the United States, residing in New Britain, in the county of Hartford and State of Connecticut, have invented and produced a new and original Design for a Tool-Holder, of which the following is a specification.

This invention relates to a design for tool-handles.

10 The drawing accompanying and forming part of this application represents a side elevation of a tool-handle, showing my design applied thereto.

15 The leading feature of my design consists in a tool-handle having a concavity and also having a quatrefoil located adjacent to such

concavity and near one extremity of the handle.

2 designates a concavity in the form of a groove in the side of a tool-handle 4, and 3 20 designates a quatrefoil located near one end of the handle and in the present instance adjacent to and in alinement with the concavity or groove 2.

Having described my invention, I claim— 25

The design for a tool-handle, substantially as shown and described.

JUSTUS A. TRAUT.
